UNITED STATES PATENT OFFICE.

ISAAC N. KLEIN, OF CLEVELAND, OHIO, ASSIGNOR TO KLEIN, GOODHART & KOCH, OF SAME PLACE.

TROUSERS.

SPECIFICATION forming part of Letters Patent No. 362,015, dated April 26, 1887.

Application filed June 12, 1885. Serial No. 168,532. (No model.)

To all whom it may concern:

Be it known that I, ISAAC N. KLEIN, of Cleveland, in the county of Cuyahoga and State of Ohio, have invented certain new and useful Improvements in Men's Garments, of which the following is a specification.

This invention relates to men's garments; and it consists in providing the seat or back portion of a pair of trousers, from the waistband to a point near the crotch, with an inner and outer seam, whereby an intervening surplus portion is produced, for the purpose of enabling such garments to be enlarged, if desired.

Figure 1 represents the back portion of a pair of pants, from the waistband down to and below the crotch, having a double seam, as above stated. Fig. 2 shows a modification of the application of the said double seam.

In cutting out these garments a sufficient quantity is allowed for a large waist measure, and the seam is sewed up in accordance with such measure. Then one or more slip-stitch or running seams are sewed from the crotch to the waistband, said rows of stitching to be at suitable distance from and within the said first row or seam as may be required to make the outlets when needed. A like course is pursued in the middle back seam of the vest.

These garments, when finished, have the take-up thus made by the extra rows of sewing 30 folded down and pressed to lie smooth. Now, should it be found necessary in fitting a purchaser of such garments to enlarge the waistband or back, the inner row of stitching is ripped or pulled out. Stretch out and press 35 the fold and they are readily fitted to the size and form of the purchaser. Other seams in garments, such as the side seams in pantaloons, the back and shoulder seams of coats and vests, and the seams under the armpits, may be 40 formed in the same manner.

By this improvement in the manufacture of ready-made clothing all of the aforesaid garments, made up in the small dimensions, are readily changed to fit persons of larger measurement without any additional sewing. 45

Having described my invention, I claim—

A pair of trousers having their seat portion united from the waistband to a point near the crotch by an inner and outer seam, whereby 50 an intervening surplus portion between the said seams is produced.

ISAAC N. KLEIN.
